ABSTRACT

The invention generally relates to probes, systems, cartridges, and methods of use thereof. In certain embodiments, the invention provides a probe including a porous material and a hollow member coupled to a distal portion of the porous material.

PROBES, SYSTEMS, CARTRIDGES, AND METHODS OF USE THEREOF

RELATED APPLICATIONS

The present application claims the benefit of and priority to U.S. provisional application Ser. Nos. 62/112,799, filed Feb. 6, 2015, and 62/211,268, filed Aug. 28, 2015, the content of each of which is incorporated by reference herein in its entirety.

GOVERNMENT SUPPORT

This invention was made with government support under GM106016 awarded by the National Institutes of Health. The government has certain rights in the invention.

FIELD OF THE INVENTION

The invention generally relates to probes, systems, cartridges, and methods of use thereof.

BACKGROUND

Paper spray has been developed for direct mass spectrometry analysis of complex samples. It has been implemented for sample analysis on commercial lab-scale mass spectrometers as well as miniature mass spectrometers. Since its development, a set of unique advantages have been shown for paper spray through a variety of applications. For example, it is easy to implement paper spray. A triangle paper substrate with a sharp tip is used as the sample substrate and the liquid sample is deposited to form a dried sample spot, such as a dried blood spot (DBS). Direct sampling ionization is performed by wetting the substrate with a solvent and applying a high voltage of about 4000 V. The solvent elutes the analytes from the sample spot and a spray ionization is generated at the tip of the substrate to produce the analyte ions for mass spectrometry analysis. Paper spray is also suitable for design of disposable sample cartridges, which is important for implementing ambient ionization for clinical, especially point-of-care (POC) analysis using mass spectrometry. A commercial aftermarket paper spray source using disposable sample cartridge has been developed and used in clinical applications.

However, there are certain limitations to paper spray. Paper spray has not interfaced well with mass spectrometers that utilize a curtain gas (e.g., Sciex instruments). Paper spray has also had issues being interfaced with miniature mass spectrometers. Also, the sharp tip of a paper spray probe directly influences the performance of the probe and mass production processes for fabricating the paper substrates, such as die cutting, have inconsistency issues for making a sharp tip from the paper.

SUMMARY

The invention provides probes that interface well with mass spectrometers that employ a curtain gas and with miniature mass spectrometers. Aspects of the invention are accomplished by adding a hollow member (e.g., capillary emitter) to a porous substrate (e.g., paper substrate) for a paper-capillary spray. The data herein show that probes of the invention had significant, positive impact on the sensitivity and reproducibility for direct mass spectrometry analysis. The paper-capillary devices were fabricated and characterized for the effects due to the geometry, the treat-

ment to the capillary emitters, as well as the sample disposition methods. Its analytical performance has also been characterized for sample analysis (such as analysis of therapeutic drugs in blood samples and quantitation of sitagliptin (JANUVIA)) in blood using a miniature ion trap mass spectrometer.

In certain aspects, the invention provides a probe that includes a porous material and a hollow member coupled to a distal portion of the porous material. In certain embodiments, the hollow member extends beyond a distal end of the porous material. Numerous different types of hollow members can be used with probes of the invention. An exemplary hollow member is a capillary tube. Similarly, numerous types of porous materials can be used with probes of the invention. An exemplary porous material is paper, such as filter paper. In certain embodiments, the porous material includes a cut within a distal portion of the material and the hollow member fits within the cut. In certain embodiments, a distal end of the hollow member is smoothed.

Another aspect of the invention provides a cartridge including a housing with an open distal end, and a probe situated within the housing. The probe includes a porous material and a hollow member coupled to a distal portion of the porous material and operably aligned to the open distal end of the housing. The housing may have numerous additional features. For example, the housing may include an opening to a porous material of the probe such that a sample can be introduced to the probe. The housing may also include a coupling for an electrode, such that an electric field can be applied to the probe. In certain embodiments, the housing includes a plurality of prongs that extend from the open distal end of the housing. In certain embodiments, the housing includes a solvent reservoir.

Another aspect of the invention provides a system that includes a probe including a porous material and a hollow member coupled to a distal portion of the porous material, an electrode coupled to the porous material, and a mass spectrometer. Any type of mass spectrometer can be used with systems of the invention. For example, the mass spectrometer may be a bench top mass spectrometer or a miniature mass spectrometer. The mass spectrometer may include a curtain gas.

Another aspect of the invention provides methods for analyzing a sample. The methods may involve providing a probe including a porous material and a hollow member coupled to a distal portion of the porous material, contacting a sample to the porous material, generating ions of the sample from the probe that are expelled from a distal end of the hollow member, and analyzing the ions. The generating step may include applying a solvent and an electric field to the probe. In certain embodiments, a solvent does not need to be used and an electric field alone applied to the probe is sufficient to generate the ions of the sample. In certain embodiments, analyzing includes introducing the ions into a mass spectrometer, such as a bench top mass spectrometer or a miniature mass spectrometer. The methods of the invention can be used to analyze any sample, such as a biological sample.

BRIEF DESCRIPTION OF THE DRAWINGS

FIG. 1 panels A-E are exemplary designs of a system.

FIG. 2 panels A-D are exemplary designs of a system with more than one spray emitter and/or a system with a three-dimensional sample substrate.

FIG. 9 panels G-I show MS/MS analysis of amitriptyline using Mini 12. For FIG. 9 panels D and G, Grade 1 paper spray is the substrate. For FIG. 9 panels E and H, ET31 paper spray is the substrate. For FIG. 9 panels F and I, paper-capillary device (3 mm emitter) is used. Imatinib in MeOH: H₂O (9:1, v:v) at 50 ng/mL and amitriptyline in MeOH: H₂O (9:1, v:v) at 20 ng/mL.

FIG. 10 panels A-B show ion chronograms recorded using QTrap 4000 with SRM transition m/z 278 $\rightarrow$ 233 for amitriptyline in blood, 200 ng/mL, using two different sample deposition methods. FIG. 10 panel A shows a sample center spotted and FIG. 10 panel B shows a sample with edge-to-edge deposition. 3 μ L blood sample was used to prepare a DBS. FIG. 10 panel C shows a calibration curve of sitagliptin in bovine whole blood, established using Mini 12 and paper-capillary spray, MS/MS with m/z 408 as precursor ion, intensity of fragment ion m/z 235 used. The inset shows the linearity for the range 10-500 ng/mL.

FIG. 11 panel A shows an exemplary disposable analysis kit for POC MS system. FIG. 11 panel B shows the change of the design for sample cartridge, from using paper spray to paper-capillary spray. FIG. 11 panel C shows analysis of Januvia (Sitagliptin) in blood using the paper-capillary spray and mini 12. FIG. 11 panels D-F show proposed methods for incorporating IS for quantitation at simple operation.

DETAILED DESCRIPTION

The invention generally relates to probes, cartridges, systems and methods for analysis of samples loaded onto a porous material with the spray ionization from a spray emitter having a hollow body (member) and a distal tip. One example of a spray emitter with a hollow body is a capillary.

An exemplary design is shown in FIGS. 1-2. A porous material, such as paper, can be used as the sample substrate. A hollow capillary, such as a fused silica capillary (i.d. 49 μ m, i.d. 150 μ m), can be coupled with (e.g. inserted into) the sample substrate. An extraction solvent can be applied onto the sample substrate and a high voltage can be applied to the wetted substrate. The solvent can wick through the sample substrate toward the capillary, extract the analytes in the deposited sample, and carry them into the capillary. The spray ionization can occur at the distal tip of the spray emitter and ions are produced. The ions may be produced for mass analysis. Spray emitters of different internal and external diameters can be used to optimize the spray ionization. The spray emitter may be made of glass, quartz, Teflon, metal, silica, plastic, or any other non-conducting or conducting material.

The sample substrate may be any shape as illustrated in FIG. 1 panels A-E and FIG. 2 panels A-D. Generally, sharp corners are removed from the sample substrate to reduce inducing a spray from the sample substrate, however, the sample substrate may have corners. The sample substrate comprises a porous material. Any porous material, such as polydimethylsiloxane (PDMS) membranes, filter paper, cellulose based products, cotton, gels, plant tissue (e.g., a leaf or a seed) etc., may be used as the substrate.

Exemplary substrates are described, for example in Ouyang et al. (U.S. Pat. No. 8,859,956), the content of each of which is incorporated by reference herein in its entirety. In certain embodiments, the porous material is any cellulose-based material. In other embodiments, the porous material is a non-metallic porous material, such as cotton, linen, wool, synthetic textiles, or glass microfiber filter paper made from glass microfiber. In certain embodiments, the substrate is plant tissue, such as a leaf, skin or bark of a plant, fruit or vegetable, pulp of a plant, fruit or vegetable, or a seed. In still other embodiments, the porous material is paper. Advantages of paper include: cost (paper is inexpensive); it is fully commercialized and its physical and chemical properties can be adjusted; it can filter particulates (cells and dusts) from liquid samples; it is easily shaped (e.g., easy to cut, tear, or fold); liquids flow in it under capillary action (e.g., without external pumping and/or a power supply); and it is disposable. In certain embodiments, the probe is kept discrete (i.e., separate or disconnected from) from a flow of solvent. Instead, a sample is either spotted onto the porous material or the porous material is wetted and used to swab a surface containing the sample.

In particular embodiments, the porous material is filter paper. Exemplary filter papers include cellulose filter paper, ashless filter paper, nitrocellulose paper, glass microfiber filter paper, and polyethylene paper. Filter paper having any pore size may be used. Exemplary pore sizes include Grade 1 (1 μ m), Grade 2 (8 μ m), Grade 595 (4-7 μ m), and Grade 6 (3 μ m). Pore size will not only influence the transport of liquid inside the spray materials, but could also affect the formation of the Taylor cone at the tip. The optimum pore size will generate a stable Taylor cone and reduce liquid evaporation. The pore size of the filter paper is also an important parameter in filtration, i.e., the paper acts as an online pretreatment device. Commercially available ultrafiltration membranes of regenerated cellulose, with pore sizes in the low nm range, are designed to retain particles as small as 1000 Da. Ultra filtration membranes can be commercially obtained with molecular weight cutoffs ranging from 1000 Da to 100,000 Da.

In other embodiments, the porous material is treated to produce microchannels in the porous material or to enhance the properties of the material for use in a probe of the invention. For example, paper may undergo a patterned silanization process to produce microchannels or structures on the paper. Such processes involve, for example, exposing the surface of the paper to tridecafluoro-1,1,2,2-tetrahydrooctyl-1-trichlorosilane to result in silanization of the paper. In other embodiments, a soft lithography process is used to produce microchannels in the porous material or to enhance the properties of the material for use as a probe of the invention. In other embodiments, hydrophobic trapping regions are created in the paper to pre-concentrate less hydrophilic compounds.

Hydrophobic regions may be patterned onto paper by using photolithography, printing methods or plasma treatment to define hydrophilic channels with lateral features of 200-1000 μm . See Martinez et al. (Angew. Chem. Int. Ed. 2007, 46, 1318-1320); Martinez et al. (Proc. Natl Acad. Sci. USA 2008, 105, 19606-19611); Abe et al. (Anal. Chem. 2008, 80, 6928-6934); Bruzewicz et al. (Anal. Chem. 2008, 80, 3387-3392); Martinez et al. (Lab Chip 2008, 8, 2146-2150); and Li et al. (Anal. Chem. 2008, 80, 9131-9134), the content of each of which is incorporated by reference herein in its entirety. Liquid samples loaded onto such a paper-based device can travel along the hydrophilic channels driven by capillary action.

Another application of the modified surface is to separate or concentrate compounds according to their different affinities with the surface and with the solution. Some compounds are preferably absorbed on the surface while other chemicals in the matrix prefer to stay within the aqueous phase. Through washing, sample matrix can be removed while compounds of interest remain on the surface. The compounds of interest can be removed from the surface at a later point in time by other high-affinity solvents. Repeating the process helps desalt and also concentrate the original sample.

In certain embodiments, chemicals are applied to the porous material to modify the chemical properties of the porous material. For example, chemicals can be applied that allow differential retention of sample components with different chemical properties. Additionally, chemicals can be applied that minimize salt and matrix effects. In other embodiments, acidic or basic compounds are added to the porous material to adjust the pH of the sample upon spotting. Adjusting the pH may be particularly useful for improved analysis of biological fluids, such as blood. Additionally, chemicals can be applied that allow for on-line chemical derivatization of selected analytes, for example to convert a non-polar compound to a salt for efficient electrospray ionization.

In certain embodiments, the chemical applied to modify the porous material is an internal standard. The internal standard can be incorporated into the material and released at known rates during solvent flow in order to provide an internal standard for quantitative analysis. In other embodiments, the porous material is modified with a chemical that allows for pre-separation and pre-concentration of analytes of interest prior to mass spectrum analysis.

In certain embodiments, the porous material is kept discrete (i.e., separate or disconnected) from a flow of solvent, such as a continuous flow of solvent. Instead, sample is either spotted onto the porous material or swabbed onto it from a surface including the sample. A discrete amount of extraction solvent is introduced into the port of the probe housing to interact with the sample on the substrate and

extract one or more analytes from the substrate. A voltage source is operably coupled to the probe housing to apply voltage to the solvent including the extract analytes to produce ions of the analytes that are subsequently mass analyzed. The sample is extracted from the porous material/substrate without the need of a separate solvent flow.

A solvent is applied to the porous material to assist in separation/extraction and ionization. Any solvents may be used that are compatible with mass spectrometry analysis. In particular embodiments, favorable solvents will be those that are also used for electrospray ionization.

Exemplary solvents include combinations of water, methanol, acetonitrile, and tetrahydrofuran (THF). The organic content (proportion of methanol, acetonitrile, etc. to water), the pH, and volatile salt (e.g. ammonium acetate) may be varied depending on the sample to be analyzed. For example, basic molecules like the drug imatinib are extracted and ionized more efficiently at a lower pH. Molecules without an ionizable group but with a number of carbonyl groups, like sirolimus, ionize better with an ammonium salt in the solvent due to adduct formation.

FIG. 1 panels B-C show two alternative designs of the sample substrate. FIG. 1 panels D-E show the section views of two exemplary designs. The capillary can be inserted into a sample substrate or between two layers of sample substrates. FIG. 2 panel A shows a configuration with multiple capillary sprayers included with a single sample substrate of a planar shape. FIG. 2 panel B shows a configuration with a cylindrical substrate. FIG. 2 panel C shows a configuration with a cone-shape substrate. FIG. 2 panel D shows an example of a sample substrate connected with multiple spray emitters. FIG. 3 shows the analysis of cocaine in bovine blood using a device as that shown in FIG. 1 panel B and a commercial TSQ mass spectrometer. FIG. 4 shows the analysis of cocaine and verapamil in methanol using a device as that shown in FIG. 1 panel A and a desktop Mini 12 mass spectrometer. FIG. 5 shows the analysis of cocaine in bovine blood using as device as that shown in FIG. 1 panel B and a desktop Mini 12 mass spectrometer.

In further embodiments the device may comprise a sprayer integrated with a sample substrate for direct sampling ionization. The sample substrate can be porous. The sprayer can be a hollow capillary or a solid tip. In other aspects a fluid sample can also be taken directly from the distal end of the capillary by capillary effect. The substrate can be wetted to serve as a conductor for the high voltage required for generating the spray ionization. In other aspects a coating of the capillary can be removed to allow light to pass through and thereby photochemical reactions to be carried on in the solution inside the capillary. In other aspects multiple spray emitters can be coupled to the sample substrate. The multiple spray emitters may be on the same side of the sample substrate or may be coupled on different sides of the sample substrate, with some acting as sprayers while others operate as a channel for transferring sample, solvent and reagents to the substrate. In other aspects a sample substrate can be covered or sealed to prevent the evaporation of the extraction solvent.

Sample Cartridges and Kits

The revolution to the MS application by the proposed POC MS system relies on the ease of use of the system by personnel un-trained with chemical analysis, such as nurses and physicians. Although the miniature ion trap mass spectrometer to be developed is versatile and applicable for a wide range of applications, special sampling kits, along with special user interface for operation, are important to make the operation simple for the end users. FIG. 11 panel A

shows an exemplary sample cartridge. The cartridge includes a housing with an open distal end. The probes of the invention are situated within the housing. The probe includes a porous material and a hollow member coupled to a distal portion of the porous material and operably aligned to the open distal end of the housing. The housing may have numerous additional features. For example, the housing may include an opening to a porous material of the probe such that a sample can be introduced to the probe. The housing may also include a coupling for an electrode, such that an electric field can be applied to the probe. In certain embodiments, the housing includes a plurality of prongs that extend from the open distal end of the housing. In certain embodiments, the housing includes a solvent reservoir. Example details about the housing are described for example in PCT/US12/40513, the content of which is incorporated by reference herein in its entirety.

The components in an exemplary sampling kit are shown in FIG. 11 panel A. It has a sample cartridge, a sampling capillary and a small bottle of solvent. The sampling capillary can be used, through capillary effect, to take a biofluid sample at amount well controlled by the volume of the capillary. This type of capillary is available at medical level for a variety of volumes, such as 5, 10, 15 μ L (Drummond Scientific Company, Broomall, Pa.) This is particularly suitable for taking blood samples with finger prick. The sample can then be deposited onto the sample cartridge, to be immediately analyzed or let dry to form a dried sample spot for later analysis.

The extraction/spray solvent can be provided in a small bottle, similar to those used for eye drops. Small amounts of solvent can be relatively consistently deposited by simply squeezing the bottle by hand. In previous test of paper spray, adverse impact on the sensitivity or quantitation precision due to the variation in solvent amount was not observed, as long as the internal standards are not incorporated through the extraction/spray solvent. Use of the bottled solvent for supply with the cartridge and capillary improves the flexibility of making special kits for manufacturing purpose. Solvents used for different applications, such as methanol, acetyl nitrile, ethyl acetate, and their combination with other solvents and reagents, can be produced with the optimized formula and provided for the best performance for the target analysis. The sample cartridge and the sampling capillary can be packed in the same package while the bottled solvent can be provided separately, which can be used with multiple cartridge/capillary packages. Alternatively, a small solvent kit for one-time use can be provided, which can be included in the same package with the cartridge and capillary.

For the sample cartridge, a paper substrate with an inserted fused capillary is used (FIG. 11 panel B). In a previous test, it was found that the sharpness of the tip for a paper spray probe and the thickness of the paper substrate have a significant impact on the desolvation of the spray process, which is less a problem for use with commercial mass spectrometer but an issue for a miniature system with a less suffocated atmospheric pressure interface. The thin paper, such as Whatman Grade 1 of 0.18 mm thickness, was found to provide a sensitivity at least 5 time higher for Mini 12 in comparison with Whatman ET31 of 0.5 mm thickness. However, the thin paper mechanically becomes soft when is wetted and is not suitable for assembly of a cartridge. It has also been recognized that fabrication of a sharp tip of a paper substrate remains challenging for industrial mass production process. Using a pulled sharp glass tip as in extraction spray,

ionization of an efficiency for nanoESI is guaranteed, but the analysis protocol for extraction spray is not as user-friendly as paper spray.

The probes of the invention combine a glass spray tip with a paper substrate for ambient ionization. The coating of a fused silica capillary, 150/50 μ m o.d./i.d. and 10 mm long, was stripped off by burning. The capillary was then inserted into an ET31 substrate serving as a spray tip. This design takes the advantages of the sample cleaning up process in paper spray and improved ionization efficiency with a sharp spray tip in extraction spray. The data below show that a sensitivity equal to the Grad 1 substrate was obtained. In the analysis of sitagliptin (JANUVIA, collaboration with Merck & Co. Inc.) in blood samples using Mini 12, an LOD or 3 ng/mL and LOQ of 10 ng/mL was obtained.

Miniature Mass Spectrometers

In certain embodiments, the mass spectrometer is a miniature mass spectrometer. An exemplary miniature mass spectrometer is described, for example in Gao et al. (Z. Anal. Chem. 2006, 78, 5994-6002), the content of which is incorporated by reference herein in its entirety. In comparison with the pumping system used for lab-scale instruments with thousands watts of power, miniature mass spectrometers generally have smaller pumping systems, such as a 18 W pumping system with only a 5 L/min (0.3 m³/hr) diaphragm pump and a 11 L/s turbo pump for the system described in Gao et al. Other exemplary miniature mass spectrometers are described for example in Gao et al. (Anal. Chem., 80:7198-7205, 2008), Hou et al. (Anal. Chem., 83:1857-30 1861, 2011), and Sokol et al. (Int. J. Mass Spectrom., 2011, 306, 187-195), the content of each of which is incorporated herein by reference in its entirety. Miniature mass spectrometers are also described, for example in Xu et al. (JALA, 2010, 15, 433-439); Ouyang et al. (Anal. Chem., 2009, 81, 2421-2425); Ouyang et al. (Ann. Rev. Anal. Chem., 2009, 2, 187-214); Sanders et al. (Euro. J. Mass Spectrom., 2009, 16, 11-20); Gao et al. (Anal. Chem., 2006, 78(17), 5994 -6002); Mulligan et al. (Chem. Com., 2006, 1709-1711); and Fico et al. (Anal. Chem., 2007, 79, 8076-8082).), the content of each of which is incorporated herein by reference in its entirety.

Discontinuous Atmospheric Pressure Interface

In certain embodiments, systems of the invention are equipped with a discontinuous interface, which is particularly useful with miniature mass spectrometers. An exemplary discontinuous interface is described for example in Ouyang et al. (U.S. Pat. No. 8,304,718), the content of which is incorporated by reference herein in its entirety.

Quantitation

A main objective of the product development is to enable simple analysis using the MS technology while retaining the mandatory qualitative and quantitative performance. Based on the previous experience in the development of ambient ionization and miniature MS systems, it is believed that the incorporation of internal standards is of a long-term benefit for production development. MRM (multi-reaction monitoring) measurement of A/IS ratio has been proved to be a robust and effective method for obtaining high quantitation precision for both lab-scale[39] and miniature MS systems. For the POC MS product development, however, the lab techniques and procedures for incorporating the IS need to be completely replaced by simple methods suitable for POC procedures.

In one embodiment, pre-printing internal standard (IS) on paper substrates can be done when manufacturing the cartridges, so the IS can be mixed into the biofluid sample when it was deposited. The sample volume is controlled by the

capillary volume. In previous studies, RSD better than 13% has been obtained; however, it was also found that inconsistency in deposition of IS and biofluid sample could have a significant adverse impact on the quantitation results. Inkjet printing can be used to despite the known amount of IS compounds within a narrow band on the paper substrate, which can be completely covered by the biofluid sample to be deposited. This is expected to significantly improve the reproducibility.

IS-coated sampling capillary is another approach for performing quantitation with a simple procedure. The IS coating inside the capillary wall is prepared by filling the capillary with the IS solution through capillary effect and then letting the solution dry. The IS is mixed into the sample filled also by the capillary effect. A very significant advantage of this method is that accurate control of the capillary volume is not required for obtaining high consistency for quantitation, since the amounts of the IS solution and biofluid sample involved are always the same. This represents a huge simplification for mass production. The data show RSDs better than 5% were obtained for blood and urine samples of amounts as small as 1 μ L. The IS coated capillaries can be packed in plastic bags, filled with air or dried nitrogen, and stored in both room and reduced temperatures for 1 to 20 weeks.

In addition to the two methods above, another method for performing a direct analyte extraction involves using slug flow microextraction (PCT/US15/13649, the content of which is incorporated by reference herein in its entirety) followed by the spray ionization using the cartridge (FIG. 11 panel F). This method has two potential advantages. The immediate extraction of the analytes helps to preserve the analytes that are unstable due to the reactions in wet biofluids, such as hydralazine in blood. Also, incorporation of IS can be performed with the extraction. In a previous study, methamphetamine-d8 was pre-spiked into the extraction solvent, ethyl acetate, for quantitation of the methamphetamine urine. Both the IS and the analyte were redistributed between the two phases based on an identical partitioning coefficient; therefore, their ratios measured for the extraction solvent can be used for quantify the original concentration of the methamphetamine in the urine sample.

Incorporation by Reference

References and citations to other documents, such as patents, patent applications, patent publications, journals, books, papers, web contents, have been made throughout this disclosure. All such documents are hereby incorporated herein by reference in their entirety for all purposes.

Equivalents

Various modifications of the invention and many further embodiments thereof, in addition to those shown and described herein, will become apparent to those skilled in the art from the full contents of this document, including references to the scientific and patent literature cited herein. The subject matter herein contains important information, exemplification and guidance that can be adapted to the practice of this invention in its various embodiments and equivalents thereof.

EXAMPLES

During the application of paper spray on different commercial mass spectrometers and the home built miniature

mass spectrometers, it has been observed that a series factors can significantly affect the performance of paper spray MS analysis. An overall best performance was observed with mass spectrometers using heated capillary, such as the TSQ (Thermo Scientific, San Jose, Calif., USA). For QTrap 4000 (Sciex, Concord, Ontario, Canada) with a curtain gas, the spray was found to be less stable and of short duration due to the curtain gas drying the solvent on paper. The Whatman ET 31 paper (Whatman International Ltd, Maidstone, ENG) of 0.5 mm thickness was used for the substrates in the commercial paper spray cartridges. However, when applying paper spray with Mini 12 mass spectrometer, the Whatman Grade 1 paper of 0.18 mm thickness was found to provide a sensitivity much better than ET 31. The thickness of the substrate affect the sharpness of the spray tip and therefore larger droplets are formed with thicker substrates during the spray. With the less sophisticated interface on Mini 12, a discontinuous atmospheric pressure interface (DAPI) without heated capillary or curtain gas, the desolvation is less efficient and the sensitivity decreases significantly for the MS analysis using ET 31 as substrates for paper spray. Unfortunately, the thin paper substrates, such as Grade 1, becomes very soft when wetted and therefore cannot be used in the cartridge. We also found that mass production processes for fabricating the paper substrates, such as the die cutting, have inconsistency issues for making a sharp tip from the paper.

In a previous study, we have used the extraction spray to achieve an improved sensitivity and quantitation precision for using Mini 12 to analyze therapeutic drugs in blood samples. A paper strip with dried blood spot was inserted into a nanoESI tube with a pulled tip for spray, where the analytes were extracted into the solvent in the tube and spray ionized through the pulled tip. The extraction spray is an example which takes advantage of the fast sample cleaning up followed by spray ionization with a well-shaped tip. The implementation of the extraction spray itself for cartridge design, however, represents a complication for the analysis protocol. With an intention to solve the observed issues for paper spray and to develop a disposable cartridge with satisfactory performance for miniature MS system, we developed a paper-capillary device (FIG. 6 panel A) to replace the paper substrate for direct sampling ionization. A systematic characterization has been carried out for the simple device in comparison with the original paper spray.

Example 1

Methods

All chemicals were purchased from Sigma-Aldrich (St. Louis, Mo., USA). Bovine whole blood was purchased from Innovative Research (Novi, Mich., USA). Chromatography papers (grade 1 and ET31) used for making paper substrate were purchased from Whatman (Whatman International Ltd, Maidstone, ENG). Fused silica tubing (O.D. 130 μ m, I.D. 50 μ m) for paper capillary spray was purchased from Molex Inc. (Lisle, Ill., USA). MS analysis were performed using a QTrap 4000 mass spectrometer (Applied Biosystems, Toronto, CA) equipped with an atmospheric pressure interface (API) using curtain gas and a home-made miniature mass spectrometer, Mini 12 with a discontinuous atmospheric interface.

For paper spray, spray substrates were prepared by cutting the paper into triangles of 6 mm at the base and 10 mm at the height. An alligator clipper was used to hold the paper substrate during the paper spray with a dc voltage of 3.5 kV

11

applied to the clipper. If not specified, elution solvents of 25 μ L and 70 μ L were used for paper spray with Grade 1 (0.18 mm thick) and ET31 (0.5 mm thick) substrates, respectively. For fabricating the paper-capillary devices, a fused silica tubing of 50 μ m i.d. and 150 μ m o.d. was cut into short pieces using a ceramic cutter. The capillary was then inserted into the ET31 (0.5 mm thick) paper substrate with a length of about 3 mm embedded in the paper.

Example 2

Sample Analysis Using Probes of the Invention

FIG. 6 panel A shows a system of the invention. The system includes a probe including a porous material and a hollow member (e.g., hollow capillary). The probe is coupled to an electrode via the porous material and the probe generates ions that are expelled from the hollowing member to a mass spectrometer, such as a miniature mass spectrometer. The paper-capillary devices of the invention could be fabricated in two different ways. A paper substrate could be split from the side using a razor blade for the capillary to be inserted in (FIG. 6 panel B); or a cut can be made halfway through on the ET31 paper substrate and then the capillary can be pushed and embedded into the cut (FIG. 6 panel C). No significant difference in performance was observed between the devices made by these two methods. However, the latter method might be more suitable for mass production of the devices.

The end of the capillary after the cut was expected to have an irregular shape with sharp micro tips, as shown with the photo (FIG. 7 panel A) taken with a microscope. These micro tips could cause split sprays. A cigarette lighter was used to burn the capillaries to remove the polyamide coatings as well as to smooth the edge at the ends of each capillary (FIG. 7 panel B). Paper-capillary devices were made using both the original and burnt capillaries, with an emitter extended out for 3 mm. They were used for analysis of bovine whole blood samples containing methamphetamine at a concentration of 100 ng/mL. For each analysis, 3 μ L blood sample was deposited onto the paper substrate and let dry to form a DBS. MeOH:H₂O (9:1, v:v) of 70 μ L was then applied as the extraction/spray solvent. A QTrap 4000 was used to perform the MS/MS analysis with [M+H]⁺ m/z 150 as the precursor ions. The ion chronograms for the characteristic fragment ion m/z 91 were extracted as shown in FIG. 7 panel C. The averaged MS/MS spectra are also shown in FIG. 7 panels D-E for comparison. A three-time higher signal intensity was obtained for use of a burnt capillary emitter. The rough edges with the original capillary could cause split sprays, which makes the spray current unstable and of lower intensity. With the polyimide coating removed, the outer diameter of the capillary was decreased by about 20 μ m, which also helps to produce smaller droplets during the spray and ultimately helps to improve the ion signals.

The impact by the extension of the capillary emitter out of the substrate was also investigated. Two paper-capillary devices were made, one with the emitter length of 3 mm and another one of 10 mm. A comparison was made between them for analysis of therapeutic drug compounds in dried blood spots on the paper substrates, each made by deposition of 3 μ L blood samples. MeOH:H₂O (9:1, v:v) of 100 μ L, was applied on the paper substrate for each analysis and the QTrap 4000 with curtain gas at the atmospheric pressure interface was used for the MS analysis. FIG. 8 panel A shows the ion chronogram recorded for analysis of 100

12

ng/mL verapamil using SRM (single ion monitoring) of m/z 465 $\rightarrow$ 165, for which the paper-capillary device with 10 mm emitter was used. A pulsed pattern was observed for the ion signal recorded continuously. The width of the pulse became wider, from 12 s at the 1st minute to 20 s at the 6th minute of the spray. However, this was not observed when an emitter of 3 mm was used. An exemplary ion chronogram recorded for analysis of 100 ng/mL amitriptyline using SRM m/z 278 $\rightarrow$ 233 is shown in FIG. 8 panel B. The pulsed spray pattern observed with the 10 mm emitter suggests that the consumption of the solvent at the emitter tip outgoes the supply of the solvent wicking through the paper substrate. The long extension of the emitter broke the balance for the solvent delivery that was held for the direct paper spray or the paper-capillary spray with a short emitter. We have also tested the substrate with the 10 mm emitter using a TSQ, which has a heated capillary but no curtain gas at the inlet. Surprisingly, the pulsed pattern was not observed, which supports the hypothesis that a faster consumption facilitated by the curtain gas contributed to the discontinuous spray.

After the optimization of the emitter on the substrate, a comparison of ionization efficiency was made among the paper sprays with the Grade 1 (0.18 mm thickness, FIG. 9 panel A), with ET 31 (0.5 mm thickness, FIG. 9 panel B), and the paper-capillary device with a 3 mm burnt emitter (FIG. 9 panel C). The spray solvent MeOH: H₂O (9:1, v:v) containing a therapeutic drug was deposited on the substrates and the high voltage was applied to generate the spray ionization. The amount of solvent used for each analysis was 25 μ L, for the Grade 1 paper spray substrate, but 70 μ L for the ET 31 paper spray substrate and paper-capillary device, which also used the thicker ET31 paper as the substrate. The first comparison was done using QTrap 4000 to analyze the imatinib spiked in the spray solvent at 50 ng/mL. MS/MS analyses with precursor ion m/z 494 showed similar intensities of the fragment peaks for the Grade 1 paper spray substrate (FIG. 9 panel D) and the paper-capillary device (FIG. 9 panel F), but an intensity 50 time lower for ET 31 paper spray substrate (FIG. 9 panel E). Similar phenomenon was observed for analysis of amitriptyline at 20 ng/mL using Mini 12 (FIG. 9 panels G-I). The intensity obtained for paper spray with ET 31 is much lower than those for Grade 1 paper spray or paper-capillary spray. The combination of the thick paper substrate with a capillary emitter represents a good strategy for cartridge design. Using ET 31 as the paper substrate, higher sample load can be used than for thinner substrate such as Grade 1. The poor ionization efficiency related to the paper thickness, however, can now be solved with the capillary emitter. During the systematic characterization of paper-capillary spray, it was noticed that the signal intensity monitored for the analyte ion fluctuated significantly from scan to scan, regardless the improvement in the average intensity. It turned out that the method of sample deposition had an unexpected influence on the stability of the analyte signals. As shown in FIG. 10 panel A, the blood sample was originally deposited at the center of the paper substrate to form a DBS, as how it was done for paper spray. However, the scan-to-scan signal fluctuation was much more severe than the paper spray. An exemplary ion chronogram recorded for SRM analysis of amitriptyline 100 ng/mL in bovine whole blood using QTrap 4000 is shown in FIG. 10 panel A. MeOH:H₂O (9:1, v:v) of 100 μ L, was applied on the paper substrate for analyte extraction and spray ionization. Fragmentation transition m/z 278 $\rightarrow$ 233 was monitored. In contrast, when the sample was deposited in the form of an edge-to-edge band, the stability of the analyte signal was significantly improved (FIG. 10 panel B). The

13

extraction solvent was applied at the base of the triangle paper substrate and wicked toward the tip; therefore, all the solvent would be forced to pass through the blood sample if it was deposited in an edge-to-edge band. This would improve the consistency of the concentration of the analytes in the spray solvent reaching the capillary emitter.

With the improved spray stability, the quantitative performance of paper capillary spray was evaluated for analysis of sitagliptin (JANUVIA) in blood using Mini 12. Samples with sitagliptin in bovine whole blood at 10, 50, 100, 500, 1000 and 2000 ng/mL were prepared for establishing a calibration curve. Blood sample of 3 μ L was used to prepared each DBS on the substrate and 75 μ L MeOH:H₂O (9:1, v:v) was used as the extraction and spray solvent for each analysis. MS/MS analysis with the protonated ion m/z 408 as the precursor was performed and the ion intensity of the fragment ion m/z 235 was plotted as a function of the concentration to establish the calibration curve as shown in FIG. 10 panel C. The linear range well covers the therapeutic window of sitagliptin (16-200 ng/mL) with RSDs better than 25% achieved.

The ultimate solution for applying MS analysis in POC applications will be dependent on the combination of a direct sampling device and a miniaturized system. Development of disposable sample cartridges suitable for ambient ionization is a promising direction for performing MS analysis with simple protocols. The paper-capillary spray inherits the features of paper spray for simple sampling and fast analyte extraction, but also takes the advantage of the high ionization efficiency and reproducibility for spray off a glass emitter as for the traditional nanoESI. This study provides a promising solution to future design of disposable sample cartridges for analyzing biofluid samples using miniature MS systems with atmospheric pressure interfaces.

Example 3

Analysis of Compounds Using Probes of the Invention

Referring now to FIG. 3, which shows an analysis of cocaine, 50 ng/mL, in bovine blood using a device similar to that in FIG. 1 panel B and a TSQ Mass Spectrometer (Thermo Scientific, San Jose, Calif.). Whatman 31ET paper of 0.4 mm thickness was used to make the substrate of a trapezoidal shape. 8 mm of fuse silica capillary (49 μ m i.d. and 150 μ m o.d.) was inserted into the substrate at a depth of about 3 mm. 5 μ L of blood sample was loaded onto the paper substrate for form a dried blood spot. 30 μ L of methanol was applied onto the substrate for analyte extraction and spray ionization. 3000 V was applied to induce the spray. a) The extracted ion chronogram recorded with SRM transition m/z 304 to 182. b) The MS/MS spectrum of precursor m/z 304.

Referring now to FIG. 4, which shows an analysis of cocaine, 10 ng/mL, and verapamil, 30 ng/ml, in methanol solution using a device similar to that in FIG. 1 panel A and a Mini 12 mass spectrometer. Whatman 31ET paper of 0.4 mm thickness was used to make the substrate of a trapezoidal shape. 8 mm of fuse silica capillary (49 μ m i.d. and 150 μ m o.d.) was inserted into the substrate at a depth of about 2 mm. 15 μ L of sample was loaded onto the paper substrate. 3000 V was applied to induce the spray. Dual-notch SWIFT wave form was applied to isolate both precursor ions m/z 304 and m/z 455; dual-frequency AC signal was applied to excite both precursors for CID. The MS/MS spectrum was recorded.

14

Referring now to FIG. 5, which shows an analysis of cocaine, 50 ng/mL, in bovine blood using a device similar to that in FIG. 1 panel B and a Mini 12 mass spectrometer. Whatman 31ET paper of 0.4 mm thickness was used to make the substrate of a trapezoidal shape. 8 mm of fuse silica capillary (49 μ m i.d. and 150 μ m o.d.) was inserted into the substrate at a depth of about 2 mm. 5 μ L of blood sample was loaded onto the paper substrate for form a dried blood spot. 30 μ L of methanol was applied onto the substrate for analyte extraction and spray ionization. 3000 V was applied to induce the spray. Figure shows the MS/MS spectrum of precursor m/z 304.

What is claimed is:

1. A probe comprising a paper porous material and a hollow member inserted into a distal portion of the paper porous material, wherein the hollow member is composed of a non-paper material.
2. The probe according to claim 1, wherein the hollow member is a capillary tube.
3. The probe according to claim 1, wherein the porous material is paper.
4. The probe according to claim 1, wherein the hollow member extends beyond a distal end of the porous material.
5. The probe according to claim 1, wherein a distal end of the hollow member is smoothed.
6. The probe according to claim 1, wherein the porous materials further comprises one or more chemicals as internal standards or for on-line chemical derivatization.
7. A cartridge comprising:
a housing with an open distal end; and
a probe situated within the housing, the probe comprising
a paper porous material and a hollow member inserted
into a distal portion of the paper porous material and
operably aligned to the open distal end of the housing,
wherein the hollow member is composed of a non-
paper material.
8. The cartridge according to claim 7, wherein the housing
comprises an opening to a porous material of the probe such
that a sample can be introduced to the probe.
9. The cartridge according to claim 8, wherein the housing
comprises a coupling for an electrode, such that an electric
field can be applied to the probe.
10. The cartridge according to claim 8, further comprises
a plurality of prongs that extend from the open distal end of
the housing.
11. The cartridge according to claim 10, further comprising
a solvent reservoir.
12. The cartridge according to claim 7, wherein the
cartridge is operably associated with a mass spectrometer
that is a bench top mass spectrometer or a miniature mass
spectrometer.
13. The cartridge according to claim 12, wherein the mass
spectrometer comprises a curtain gas.
14. A method for analyzing a sample, the method comprising:
providing a probe comprising a paper porous material and
a hollow member inserted into a distal portion of the
paper porous material, wherein the hollow member is
composed of a non-paper material;
contacting a sample to the paper porous material;
generating ions of the sample from the probe that are
expelled from a distal end of the hollow member; and
analyzing the ions.
15. The method according to claim 14, wherein the
generating step comprises applying a solvent and an electric
field to the probe.

16. The method according to claim 15, wherein the wherein the mass spectrometer is a bench top mass spectrometer or a miniature mass spectrometer.

17. The method according to claim 14, wherein analyzing comprises introducing the ions into a mass spectrometer. 5

18. The method according to claim 14, wherein the sample is a biological sample.
